UNITED STATES PATENT OFFICE.

ELI SHUPE, OF RACINE, WISCONSIN, ASSIGNOR TO GOLD MEDAL CAMP FURNITURE MANUFACTURING CO., OF RACINE JUNCTION, WISCONSIN, A CORPORATION OF WISCONSIN.

FOLDING STOOL.

No. 801,405.

Specification of Letters Patent.

Patented Oct. 10, 1905.

Application filed November 28, 1902. Serial No. 133,030.

To all whom it may concern:

Be it known that I, ELI SHUPE, a citizen of the United States, residing at Racine, in the county of Racine and State of Wisconsin, have 5 invented certain new and useful Improvements in Folding Stools, of which the following is a specification, reference being had to the accompanying drawings, forming a part thereof.

The main objects of this invention are to 10 limit the spreading of the legs when the stool is opened for use without undue strain on the seat and the fastenings attaching it to the legs, to avoid strain on the pivot-pins and splitting or breaking the legs next to said pins, to ad- 15 mit of the employment of light material for the legs without sacrificing strength and durability, and generally to simplify and improve the construction of stools of this class.

It consists in certain novel features in the 20 construction, arrangement, and combinations of parts, as hereinafter particularly described, and pointed out in the claims.

In the accompanying drawings like letters 25 designate the same parts in the several figures.

Figure 1 is a vertical projection of the improved stool when spread for use. Fig. 2 is a like view of the same when folded. Fig. 3 is a cross-section on the line 3-3, Fig. 2, showing the pivot-piece and the manner of attaching 30 the legs thereto. Fig. 4 is a plan view, on an enlarged scale, of a modified form of the pivot-piece; and Fig. 5 is a side elevation of the same.

a designates the pivot-piece, which is of an 35 nular form and has flat parallel exterior faces on opposite sides, with opposing oblique shoulders or abutments *b b* projecting outwardly from said faces.

c c are the legs, which for the sake of light- 40 ness are preferably made of hard wood and are preferably rectangular in cross-section, as shown. They are secured about midway between their ends to the opposite faces of the pivot-piece *a* by bolts or rivets *d d*, which

45 serve as pivot-pins and pass through holes in said pivot-piece and in the legs midway between the shoulders *b*. Rivets are preferably employed for the pivot-pins, and their heads are placed inside of the pivot-piece *a*, while 50 they are upset at their outer ends over washers *e e*.

f is a flexible seat which may be conven-

iently made of canvas or similar material. It is approximately square in shape and provided at the corners with pockets *g*, which 55 are slipped over the upper rounded ends of the legs and are secured thereto by nails *h h* or other means.

The pivot-piece may be conveniently and 60 economically cast in the form in which it is shown in Figs. 1, 2, and 3, and ordinary gray iron has been found to be sufficiently strong and quite satisfactory for the purpose. It may, however, be stamped out of steel or wrought metal in the form shown in Figs. 4 65 and 5, the ends of the band forming the ring *a'* being lapped, drilled, or punched and secured together by one of the pivot-pins or rivets *d*, as shown in Fig. 4. When formed out of steel or wrought metal, the shoulders 70 or abutments *b'* are punched therefrom and bent outwardly perpendicular to the faces of the ring.

It will be apparent from the foregoing description, in connection with the drawings, that 75 when the legs are spread they will bear on opposite sides of the pivot-pins or rivets *d* against the shoulders *b* or *b'*, which will confine and compress the wood of the legs cross-wise of the grain and prevent the same from 80 splitting or breaking. At the same time the spreading of the legs will be limited by said shoulders and undue strain on the seat *f* and pocket-pieces *g* or other fastenings at the upper ends of the legs will be avoided. The 85 flat faces of the pivot-piece *a*, against which the legs are held by the rivets *d*, also tend to brace and hold the legs in place. The construction of the pivot-piece, with its oblique shoulders *b* or *b'*, and the manner of securing 90 the legs thereto make it practicable to use comparatively small light legs.

Various changes in minor details of construction may be made within the spirit and intended scope of the invention. 95

I claim—

1. In a folding stool the combination of a pivot-piece, having opposing oblique shoulders on its outer faces, legs secured to said pivot-piece between said shoulders by pins whereby the legs are clamped on opposite sides of their pivots between said shoulders when the stool is spread, and a flexible seat attached to said legs, substantially as described. 100

2. In a folding stool the combination of an annular pivot-piece having parallel flat faces on opposite sides thereof and opposing oblique shoulders projecting outwardly from 5 said faces, legs pivotally secured to said pivot-piece by pins passing through them and the pivot-piece between said shoulders and the ends of the legs, whereby the legs are clamped on opposite sides of their pivots between said 10 shoulders when the stool is spread, and a flexible seat attached to said legs, substantially as described.
3. In a folding stool the combination of an annular metallic pivot-piece having flat parallel faces on opposite sides with opposing oblique shoulders projecting outwardly from each face and holes midway between said shoulders, legs secured to said pivot-piece by pins passing through them and the holes in 15 20 said pivot-piece, and a flexible seat attached
- at its corners to the upper ends of the legs, substantially as described.
4. In a folding stool the combination of an annular metallic pivot-piece having flat parallel faces on opposite sides with opposing oblique shoulders projecting outwardly from each face, legs of rectangular cross-section secured to said pivot-piece midway between said shoulders by rivets or pins passing transversely through the legs and pivot-piece, and 25 30 an approximately square flexible seat provided at the corners with pockets in which the upper ends of the legs are secured, substantially as described.

In witness whereof I hereto affix my signature in presence of two witnesses. 35

ELI SHUPE.
